GUN TURRET

René E. Duplessis, Beverly, Mass., assignor to
 United Shoe Machinery Corporation, Flemington, N. J., a corporation of New Jersey

Application June 27, 1946, Serial No. 679,827

4 Claims. (Cl. 89—37)

1

This invention relates to gun-turrets, and more particularly to those in which a plurality of guns may be directed simultaneously for their discharge, this being preferably under the control of a plurality of gunners.

The invention has as an object the mounting of the plural guns stably within a quite limited space, yet in such a manner that ready access to all may be had by the gunners, the ammunition effectively and reliably supplied to them and spent ammunition-parts conveniently disposed of. It is also desired to direct the gun fire by simple and compact motor mechanism and, alternatively, by manual means.

To attain this object, I combine with a turret rotatable in azimuth a gun-carrier rotatable in elevation upon the turret, said carrier consisting of a plurality of separable sections each having means for mounting one or more of the guns. There is thus furnished means for moving the guns together in the two planes, the sectional formation of the carrier making possible a structure which is strong and yet relatively light and in which the guns may readily be installed. As herein disclosed, the guns are at different levels and in different numbers in the carrier-sections, reducing the space required, increasing the accessibility and giving a structure balanced with respect to gun-discharge. Mounting means for different portions of each gun are so disposed in the carrier as to insure rigidity and to give a compact arrangement. This mounting means in itself presents novelty. For gun-groups at opposite sides of the center of the carrier there are opposite groups of ammunition-containers or annular troughs in the turret, the troughs being nested one within another and preferably being arranged concentrically about the axis of rotation of said turret. This arrangement gives a very large storage-capacity in a limited space, with the containers symmetrically arranged for most direct delivery to the respective guns. The containers or troughs are shown as carried upon the floor of a basket or substantially round container depending from the turret floor, there being a floor-space between the inner troughs for the reception of spent ammunition-parts, as cartridge-cases and the links of cartridge-belts. To this space the ammunition-parts are delivered by ejection-chutes individual to the guns and to the parts and mounted upon transverse walls of the gun-carrier, which also support the mounting means for one portion of each gun. In the link-chutes may be included means, as a longitudi-

2

nally extending spring or springs, for preventing, by their engagement, angular displacement and clogging of the links. At the front of the basket-floor, between the containers and in said floor, are doors or removable sections through which access may be had to the turret and communication permitted between said turret and a tank upon which it may be mounted. To relieve the breech mechanism of the guns of the load which would be created by the elevation of the ammunition-belts from the containers, there is lifting motor means for each belt disposed in the most convenient manner upon the troughs or upon the turret, together with manually operable means for initially elevating the belts from certain of the troughs. To guard against the accumulation of a belt at the outgoing side of its motor mechanism if the operation of its gun ceases, means may be provided for disconnecting power from the motor means, this disconnecting means being controlled by a member movable by the accumulating belt. To rotate the turret and carrier for the direction of the guns, there is a motor mechanism for each attached to a wall of the turret, it being geared directly to the turret or to the carrier. Each of two gunners in the turret has manual means by which one of the gun-directing movements may be produced as a substitute for the motor-drive, and there is means whereby either the manual means or the motor mechanism may be effectively connected selectively to the gearing by which either the turret or carrier is rotated. This connecting means, as herein disclosed, consists of a clutch with which is associated means for making the corresponding motor mechanism ineffective as the manual means becomes effective. The preferred form of support upon which the gun-carrier is rotatable consists of brackets spaced transversely of the turret and attached to the front and upper turret-walls. With a crew of two gunners the brackets are respectively in front of their gun-positions, and their motor-controlling or grip mechanisms are attached to the brackets, which, because of their size and location, afford protection to both the gunners and the grip mechanisms. To valves which govern the azimuth and elevation motor mechanisms, the grip mechanisms of the two guns are joined by a lever- and cable-system, so disposed as to avoid interference with the crew or the contents of the turret. In the cables are shown loaded springs by which they are maintained taut.

In the accompanying drawings illustrating a particular embodiment of my invention,

Fig. 1 is a central, vertical, longitudinal section through the improved turret, viewed from the left when inside facing the front of said turret, but with the gun-carrier in elevation;

Fig. 25, an enlarged vertical transverse section through a gun-mount on the line XXV—XXV of Fig. 6.

At 30 (Fig. 1) is indicated a fragment of a support which may, for example, be the top wall of

a tank. In the supporting wall is a circular opening having secured within it a bearing-ring *t* for the turret T. The ring has a portion 32 which is attached to the support 30, and this, with an upper portion 34 joined to 32 by screws, furnishes an annular raceway for bearing-balls 36. Upon the balls an inner annulus 38 is free to turn, and to this is secured the annular flange 40 of the turret. This turret has opposite upwardly and inwardly inclined side walls 42, 42 and a convex or inclined top wall 44. At the front between the side walls is an opening, across the center of which extends upwardly from the flange 40 to the top wall 44 a guard and deflector-bar 46. The turret has a rearward extension 48, the bottom wall 50 of which is located above the level of the flange 40. Rising at each side of the turret, partly from the top wall 44 and partly from the top of the extension 48, is a vertical wall 52 surrounding a hatchway-opening. In each opening may be movable a sight S, the arrangement of which will be described later, and through each of which openings one of the two men seated in chairs C, C and forming the gun-crew may scan. The chairs rest upon a crossbar 53 suspended from the turret-flange 40. Carried by hangers 54 depending from the flange 40 is a basket having a bottom or floor 56, parallel rings 58, 58 and intermediate inclined stays 60. The basket is open at the front, there being in it a considerable space in the rings 58, and at the center and front of the floor is an open space provided at the front with a door 64 (Fig. 8). A section 65 of the floor adjacent to the door may be removable, and through the opening thereby provided communication may be had between the turret and tank. Through it the crews may pass or they may remove spent ammunition swept from the turret floor. The door 64 furnishes entrance to the turret for the crew. It may both swing upwardly on hinges and be removable bodily.

The turret is designed to carry a plurality of guns G, preferably six in number. These guns are held in pairs at three levels normally fixed against movement upon a rotary carrier R. The carrier is in the form of a skeleton-drum made up of three generally cylindrical sections bolted together (Fig. 5), there being a central section 70, a right-hand section 72 and a left-hand section 74, this relation being as viewed from the gunner's stations. Each of the sections 72, 74 has a vertical transverse outer wall 76 and an inner wall 78. At the center of each outer wall is a hub 80 in which is fixed a trunnion shaft 82 having a bearing at 84 in a fixed bracket 86, a horizontal portion of which is secured to the front wall of the turret and a vertical portion secured to the top wall (Figs. 1 and 3). Each bracket is heavy and its points of attachment effectively distribute the stresses it receives. With the six guns situated at three different levels, ready access to all may be had from the opposite ends of the carrier. All the guns are aimed simultaneously during action, in elevation by rotation of the carrier upon its brackets 86 and in azimuth by rotation of the turret upon its ring *t*. The manner in which these movements are effected will be hereinafter described. The excess of weight of the carrier at the front, due to the projecting barrels of the guns, is counterbalanced by opposite tension devices using springs 88, 88 connected to the floor 56 of the basket and to the hubs 80 of the carrier (Fig. 2).

75 The lower and upper pairs of guns G are lo-

cated within the carrier-section 70, with the forward portion of each gun-craddle *g* supported by a device *m* (Figs. 5 and 6) upon a projection 90, from the peripheral wall and extending between a vertical transverse partition or wall 92 (Fig. 5) at the center of the section and an outer inwardly projecting flange 93 (Figs. 5 and 6). In each of the side sections 72 and 74 is one of the guns of the intermediate pair, with the forward portion of its cradle supported by a device *m* (Figs. 5 and 7) upon a projection 94 from the peripheral wall and extending between the transverse walls 76 and 78. The guns in the carrier-sections 72 and 74 are mounted at the level of and adjacent to the trunnions 82, while the guns in the section 70 are spaced substantially equally on opposite sides of the center of said section, and above and below the axis of the trunnions. This arrangement tends to balance the shock of the gun-discharge. For adjustably supporting the rear of each gun with respect to its carrier, there is means guided at 96 or 98 (Figs. 4, 6 and 25) for movement vertically with the rear portion of said gun. For the upper and lower pairs of guns this supporting means is upon the inner walls 78 of both side sections 72 and 74 and for the intermediate pair at 98 upon the outer wall 76 of both of said sections (see the six wall bosses in Fig. 5). Both the forward and rear supports may be the same for all of the six guns, so but one pair will be described. In one of the projections 94 (Fig. 7), for example, from the carrier-walls is a generally vertical passage, in which the shank 100 of a pivot member 102 of a device *m* is free to turn. At its upper extremity the member 102 receives a horizontal pin 104, upon which may turn a yoke 106 clamped by a bolt 108 to the gun-craddle *g*. Upon this forward mount the barrel of the gun has a universal movement, to swing both horizontally and vertically. It receives the greater part of shock of discharge of the gun, and the mounting projections 90 and 94 are from the peripheral carrier-wall where the sections are bolted together and are most rigid, thus offering the maximum resistance. Upon the rear guide 96, arranged for convenient access by the gunner, a slide 110 is movable (Fig. 25), it having a horizontal extension 112. Threaded in the guide is a screw 114 receiving a portion of the slide between a peripherally notched finger-piece 116 and a flange 118. Rotation of the screw will raise or lower the slide and its extension, and this adjustment may be maintained by a detent 120 pivoted upon the slide and engaging a notch in the finger-piece. Into the extension 112 is threaded a sleeve 122. Within the sleeve and splined to it at 124 a spindle 126 is rotatable by a head 128 similar to the screw 114. The lower portion of the extension is divided longitudinally, to be drawn in to clamp the sleeve by a screw 130 passing through an opening in one portion and threaded into the other. Straddling the sleeve 122 between the head 128 and a collar 132 fast upon the opposite end of the spindle are depending lugs 134, 134 of a guide member 136. In lower ways 138 in this member a slide 140 is movable longitudinally of the gun, it having an upwardly extending pivot-projection 142 entering a slide 144 movable in upper ways 146 in the slide 140, with a capacity for some lateral play. Rotation of the spindle 126 turns the sleeve 122, when this is unclamped, thus shifting the guide member 136 horizontally. The slide 144 carries a lug 148 for connection by a bolt 149 to spaced lugs 150 depending from the rear of the gun-craddle *g*.

The lugs 146 to which are connected four guns in the central section 70 of the carrier are inclined outwardly from each of the slides 144 to give space in which access may better be had to the breech mechanism and the empty cases and the links of ammunition-belts discharged. Openings 152 in the vertical walls of the sections permit, among other purposes, the gun-crew to reach from one to another.

10 For the purpose of bore-sighting a gun, with the clamping screw 130 of its mount backed off and the detent 120 released, the muzzle of the gun projecting from the turret through an opening 153 in the front of the carrier may be raised or lowered by turning the screw 114 and thereby correspondingly moving the rear of the cradle, while the gun may be swung laterally by rotation of the spindle 126 and sleeve 122. During these adjustments, the forward portion of the cradle pivots respectively at 104 and 100. The capacity for longitudinal movement of the slide 140 accommodates the rectilinear movement of the slide 110 to the arcuate swing of the cradle-projections 150 during the adjustment of the gun in elevation, while a similar compensation during adjustment in azimuth is obtained between the movements of the guide member 136 and lugs 150, in consequence of the pivoting of the slide 144 at 142 and the lateral play of said slide in the ways 146. This mounting, by locating a considerable part of the elevation-varying mechanism at one side of the gun, gains economy in space, so much needed where the guns are to be located one above another in a movable carrier, while ample bearing surfaces between all movable parts are still provided. All the elements through which the adjustments are to be made are conveniently arranged close together at the rear of the gun. It is further to be noted, that by making the adjustment of the outwardly inclined guns in elevation by movement in a plane at right-angles to that in azimuth instead of in the plane of their inclination, the adjustment does not introduce an error into the azimuth setting.

15 Ammunition for the guns is supplied in the form of belts of the well-known disintegrating-link type, the cartridges *L* being clipped in the successively interlocked links *l* (Fig. 9). The belts are held folded back and forth in successive layers in magazine-troughs, of which there is one for each gun (Fig. 8). The troughs are arranged in two groups or sections *A*, *A*¹ of three each, a group serving the group of guns at the corresponding side of the carrier *R*. They are generally arcuate and concentric, the troughs of a section being constructed as a unit, with a bottom wall 160 and vertical side walls 162. In each section, the outer trough *a* serves the outermost gun in the carrier or the gun in the corresponding outer carrier-section 72 or 74. The next or intermediate trough *a*¹ supplies the upper gun at that side of the center-section 70 of the carrier, while the inner trough *a*² is for a lower gun in that section. The concentric troughs are enclosed within the substantially round container or basket and are nested one within another to provide the maximum storage-space for the piled loops of ammunition-belts for the plural guns, and with the thicker primer-ends of the cartridges at the outside, at a greater radial distance from the axis of the basket than the bullet-ends, the belts conform naturally to the curvature of the troughs. To relieve the breech mechanism of the guns from the load resulting from the

lifting of the belts the entire distance from the troughs, there is associated with the forward extremity of each trough a booster or belt-elevating mechanism. This mechanism may be of a conventional type in which a cylinder 164 (Figs. 9 and 10) is rotated by an unillustrated motor contained within it, the cylinder having secured side by side upon its periphery toothed flanges 166, 166 so formed as to engage the cartridges L in the belts at opposite sides of their longitudinal centers occupied by the links l. Each booster is carried upon a casing, two each designated by the character 168 (Fig. 9) being attached to the lower interior portion of the turret T, while a casing 170 is fastened directly to the top of the trough a. Between the upper casings 168, 168 and lower casings 172, 172 attached to the top of the troughs a¹ and a² extend belt-guiding chutes 174, 174. The chutes for the troughs a² may be of sheet-metal; those for the troughs a¹, which are longer and more curved, are of the linked type. From the casings 170 (Figs. 8, 9) of the troughs a the cartridge-belts pass directly to the breach mechanisms of the guns in the outer sections of the carrier R. Attached to each of the casings 168 and 170 and to the corresponding gun is a flexible chute 175 (Fig. 9) similar to the lower chute 174 for the trough a¹, this chute 175 guiding the cartridge-belt and bending therewith during the oscillation of the carrier.

In each of the casings 172 is rotatably mounted a cartridge-engaging cylinder 176 similar to the cylinders 164. To the ends of the spindles 178 of these cylinders a hand-crank 180 may be applied and rotated to lift the cartridge-belt from the corresponding trough when the end of said belt is to be delivered initially to the breech mechanism of the gun. No such aid is necessary for the trough a because of the short and direct path to the gun. The direction of advance of the belts to the guns is such that those for the troughs a¹ and a² pass below the booster-cylinders 164, while for the trough a the belt travels above the cylinder. In each case, there is opposite and in close proximity to the cylinder a curved guide-wall 182 (Figs. 9, 10). Each wall is pivoted at 184 to its casing and is held normally in proximity to the booster-cylinder to place the cartridge-belt in engagement with the teeth 166 for its advance. This position of the wall is yieldably maintained by a spring 186 at each side, this surrounding a headed pin 188 extending along the side of the casing from a lug 190 fixed to the wall 182, said spring abutting at its ends against the head of the pin and against a bracket 192 on the casing through which said pin passes. A switch 194 is carried upon each of the casings 170 or 172 and may be opened when its actuating member 195 (Fig. 10) receives contact of a projection 196 from the corresponding wall 182. This switch controls the circuit of the booster-motor. If, with said motor in operation, the corresponding gun jams and ceases to feed the cartridges into the breech mechanism, piling up of the belt outside the booster-casing is prevented by yield of the wall 182 against its springs, as the resistance offered by the belt to advance causes it to force out the wall, opening the circuit of the booster-motor. The cartridge-belt therefore remains at rest in the trough until renewed fire of the gun takes up any accumulation of cartridges between the casing and the gun. When this occurs, the springs 186 restore the wall 182 to its normal relation and the switch 194 closes again, starting the booster in operation. A sleeve 198 is shown surrounding the spring 186

between the bracket 192 and the head of the pin. The length of the sleeve is such that the movement of the casing-wall is limited by the contact with it of the pin-head, and the cartridges cannot accumulate and clog later advance by rolling up and riding over one another in a wider space.

After a cartridge has been fired, the empty case and the disengaged connecting link of its belt are separately received by ejection-chutes 202, 204, 206 and 208 secured to the walls 92, 16 and 78 of the carrier R (Figs. 5, 6 and 7) and therefrom discharged upon the central portion of the floor 56 of the turret, from which they may be removed at intervals upon opening the floor-section 65 (Fig. 8). The chutes may each be rectangular in cross-section with an upper receiving throat and a lower delivery-opening. The throats lie in proximity to the portions of the breech mechanisms of the guns from which the cases and links are ejected. The delivery from the carrier is through an opening 200 (Fig. 7) in the peripheral wall of the section in which the chute is located and above the receiving portion of the basket. When the guns are raised at a considerable angle in elevation, the ejected parts are deflected downwardly and rearwardly by the front turret-wall, the bar 46 and an apron 201. This apron is secured to the trough-walls 162 and extends over the turret-flange 40. Attached to one side of the wall 92 of the section 70, with its receiving throat near the center of the wall, is the case-chute 202 for the upper gun (Figs. 5 and 6), its delivery opening being above the wall-opening in that section. Below and outside the case-chute 202 is a case-chute 204 for the corresponding lower gun. Supported upon the wall 92 in front of the case-chutes is a link-chute 206 for the upper gun and beside and below it a link-chute 208 for the lower gun. Upon the opposite side of the wall 92 are four similarly arranged chutes for the other pair of guns in the central section of the carrier. Upon each of the walls 76 of the side sections 72 and 74 of the carrier is a case-chute 210 for the gun at that side (Figs. 5 and 7), and into this chute delivers a link-chute 212 mounted on the inner wall of that section. From Figs. 6 and 7 it will be seen that the lower guns of section 70 are mounted somewhat to the rear of the companion-guns. This permits the link-chutes 206 and 208 to be placed side-by-side, parallel to each other. Simple straight chutes may thus be used and clogging avoided. Brackets 214 (Fig. 6), by which the link-chutes are supported, have slot-and-screw connections 216 to the carrier, providing for the more exact registration of their receiving throats with the breech mechanisms of the guns.

The two sights S, of any desired type, by which the fire of the guns may be directed by the gunners in the chairs C, C are mounted respectively at the centers of two yokes, each having arms 220, 220 (Figs. 1, 11 and 12). The outer arm of each yoke is pivoted at 222 in the outer wall 52 of the corresponding hatchway, while the inner arm is joined to one extremity of a sleeve 224 surrounding a spindle 226 rotatable in spaced lugs 228, 228 depending from the top wall 44 of the turret. Each of the inner yoke-arms is joined by a link 230 to a crank-pin 232 projecting from one of the walls 76 of the carrier R. Thus, the movement of rotation of the carrier which swings the gun in elevation is communicated to the sights to shift them through the same angle. For the direction of the guns

in azimuth, the sights, of course, rotate with the turret.

To produce the movement of the guns in azimuth by the rotation of the turret T and in elevation by the rotation of the gun-carrier R, there is mounted in the rear extension 48 of the turret a casing 250 (Fig. 22) in which are a motor and two pumps operated by said motor. The motor and pumps may be conventional and are not illustrated. The motor receives current through a cable 252 (Fig. 2) and a collector device contained within a casing 254 located at the center of the turret-floor 56. From the pumps piping 256 (Fig. 22) leads to azimuth motor mechanism M (Fig. 3) and piping 258 to elevation motor mechanism M' (Fig. 3), by which the guns are given their respective directional movements.

To consider first the azimuth mechanism M, and referring to Figs. 1, 13 and 14, there is attached by brackets 260 to the flange 40 of the turret at the rear, a casing 262 made up of a plurality of sections. To one extremity of the casing is attached an hydraulic motor 264 receiving oil under pressure through the piping 256. Its driving shaft 266 (Fig. 14) is joined to a main shaft 268 journaled in the casing 262 and carrying a worm 270 of reducing gearing including successively a worm-wheel 272 (Fig. 13), a pinion 274 and a gear 276, the latter meshing with an internal gear 278, formed upon the bearing-ring t (Fig. 1). The rotation of the motor 264 is thus communicated to the turret at a greatly reduced rate, so it may be turned in azimuth through an unlimited angle.

Instead of driving the turret by a motor, as just described, it may be desirable for one of the gunners to turn it manually. Means is furnished for the accomplishment of this by the man at the right of the turret. In a section of the casing 262 is clutch mechanism c (Figs. 14 and 15), which may connect the shaft 268 to or disconnect it from a flexible shaft 280 which, at its opposite end, is joined to a shaft 282 rotatable in a casing 284 (Fig. 17). This casing supports the motor-controlling mechanism of the right-hand man, it being attached by a bracket 285 to the rear side of the right-hand carrier-bracket 86. Journaled in the casing transversely of the shaft 282 is a short horizontal shaft 286, upon which is fixed a spiral gear 288, with which meshes a spiral pinion 290 on the shaft 282. Upon the opposite ends of the shaft 286 are fastened crank-arms 292, 292, each having a hand-hold 294. Grasping these hand-holds, with the clutch c engaged, the right-hand gunner may turn the flexible shaft 280 and thereby the shaft 268 and, through the intermediate gearing, the turret T. With the clutch disengaged, rotation of the shaft 268 normally driven by the motor 264, is not communicated to the shaft 280, and the hand-cranks 294 are at rest.

A convenient form of clutch for the present purpose is of the double friction type. To an extension 296 (Fig. 14) of the shaft 268 a disk 298 is splined and has arranged for engagement with its opposite faces disks 300 and 302, the hubs of which are rotatable upon bearings 304 about the extension 296. The disk 302 is connected to turn the shaft 280. Surrounding the disk-hubs are expansion-springs 306, 306, each abutting at its inner end against its disk and at the opposite end against a thrust-bearing 308. The outer disks are compelled to turn together by intermeshing projections 310 (Fig. 15) from

their inner faces, while being capable of limited movement longitudinally of the shaft. Arranged to turn in the casing 262 are opposite spindles 312, 312, having, between the marginal portions of the disks 300, 302 and outside the disk 298 and the disk projections 310, pairs of diametric cam-projections 314, 314. The spindles 312 may be turned by a hand-yoke 316 (Fig. 13) fixed to their outer ends. With the spindles so positioned that the cams lie parallel to the inner faces of the outer disks and out of contact therewith, the springs 306 force the outer disks into such engagement with the intermediate disk that they all turn together, the latter disk shifting along the extension 296 as may be necessary to equalize the pressure. The disk 302 therefore drives the shaft 280 for the manual rotation of the turret. Turning with the yoke 316 is an arm 318 which is joined by a link 320 to an arm 322 on the plug of a by-pass-valve 324 adapted to connect the opposite sides of the pressure-line 256 from the pump to the motor 264. As appears in Fig. 16, when the clutch c is disengaged, the valve is closed and pump-pressure is transmitted to the motor for its operation. When, however, the yoke 316 is actuated to engage the clutch for the manual rotation of the turret, the link 320 opens the valve so the motor circulates the oil idly therethrough, relieving the gunner of the burden of any substantial resistance.

The power-rotation of the carrier R and consequent movement of the guns in elevation is effected by the motor mechanism M', see Figs. 2, 19, 20 and 21. Here, an enclosing sectional casing 330, is attached by brackets 332 to the upper wall 44 of the turret near its center. An hydraulic motor 334 supplied with pressure through the piping 258 is attached to the casing with its driving shaft 336 connected to a main shaft 338 journaled within the casing. Worm-gearing 340 and a series of spur-gears 342 furnish a speed-reducing drive to a gear-segment 344 fixed to the central section 70 of the carrier R. By providing slot-and-screw connections between the casing 330 and the brackets 332, the position of the former may be varied and correct meshing of the gearing 342 with the segment obtained.

To enable the left-hand man to direct the guns manually in elevation, the shaft 338 is connected by bevel-gearing 346 to a shaft 348 journaled in the casing 330. A clutch c¹, which may be in all essential respects similar to the clutch c, joins the shaft 348 to a shaft 350 through a universal coupling 352. A second universal coupling 352 connects the shaft 350 to a short shaft 354 journaled horizontally in a casing 356 attached to the left-hand carrier bracket 86. The universal connections permit the adjustment of the casing 330. The shaft 354 carries a pinion 358 meshing with a gear 360 on a shaft 362 rotatable in the casing below the shaft 354. Upon the opposite extremities of the shaft 362 are opposite hand-cranks 364, the rotation of which by the left-hand gunner is transmitted back through the clutch c¹ and the gearing to the carrier R. The clutch is engaged and disengaged by a yoke 366, as in the azimuth mechanism, and the actuation of a by-pass-valve 368 upon the engagement of the clutch relieves the operator of the resistance of the motor 334. It is to be observed that save for the momentary shift from motor to manual-drive and the reverse, both the turret and gun-carrier are always under the control of their driving mechanisms. This, since these mechanisms for the turret and carrier are connected directly to

the respective gearing mechanisms through which the driving force is transmitted. Further, because of this independence of the azimuth and elevation-drives from each other, they may be utilized together to control the direction of the guns. If, for example, the azimuth motor mechanism becomes inoperative, the right-hand gunner may engage the clutch *c*, simultaneously opening the by-pass valve 324. Then he may rotate the turret through the cranks 292, while the other gunner continues to employ his hydraulic mechanism. Both the mechanisms *M* and *M'* provide a direct gear-drive for the respective gun-directing means, all the elements of these mechanisms being well-removed from the space required for the gun-crew and their equipment.

As is customary, the operation of the azimuth-motor 264 and the elevation-motor 334 is controlled by valves, these not being illustrated but being contained in the casing 250 and actuated through stems 376 and 378 respectively (Fig. 22). Connections are provided through which the usual grip mechanisms of both men in the turret may operate both valves, and, taking first the connections for the right-hand man, they may be seen in Figs. 1, 17, 18, 22 and 23 with the grip mechanism for the left-hand man shown in front elevation in Figs. 19 and 21. In a rearward projection 380 from the casing 284 (Fig. 17) the shank 382 of a yoke 384 is arranged to turn about a generally vertically axis. The corresponding grip-mounting for the left-hand man is in a projection from the casing 356 (Fig. 21), like elements of the two grip mechanisms being identified by the same reference characters. The main support of each of the two mechanisms is the corresponding bracket 36, at the rear of which it is located. This relatively massive bracket furnishes a shield against gun-fire for the grip mechanism and, to some extent, for the gunner. Pivoted at 386, between the arms of the yoke 384 is the body 388 of the grip mechanism, to the opposite sides of which are attached hand-holds 390, 390. Projecting from the inner or rear portion of the yoke 384 is an arm 392 to the end of which is pivoted a link 394 adjustable as to length. The opposite extremity of this link is joined to one arm of a bell-crank lever 396 fulcrumed for horizontal movement upon the adjacent wall 42 of the turret. These connections are shown in Fig. 23 as for the left-hand man. To a second arm of the lever 396 two links 398, 398 are connected by a common pivot. From the respective links cables 400, 400 lead, at first oppositely and then side by side along the side of the turret, and then together at right angles through the extension 48, being guided by sheaves 402 rotatable upon the turret-walls and the casing 250. Fixed to the stem 376 of the valve in the casing controlling the azimuth-motor 264 is a bell-crank lever 404 to a horizontal arm of which opposite links 406, 406 are pivoted, and to these two links the cables 400, 400 approaching from opposite directions are respectively attached. So, as the gunner swings the hand-holds 396 laterally, the connections just outlined open or close the valve, this correspondingly moving the turret to direct the guns *G* in azimuth. To rotate the carrier *R* for similar control of the elevation of the guns, a vertical link 408 is pivoted to the front of the grip-body 388. The lower end of the link is pivoted to one arm of a bell-crank-lever 410 fulcrumed about a horizontal axis upon the mounting of the spindle 382 of the grip mechanism. An adjustable link 412 joins the lever 410 to a second bell-crank-

lever 414 fulcrumed about a vertical axis upon the adjacent tank-wall. As with the azimuth-controls, double links 416, 416, cables 418, guided over sheaves 420, double links 422, 422, and a bell-crank-lever 424 join the lever 414 to the stem 378 of the valve governing the elevation-motor 334. Since it is desired that both men in the turret shall be able to direct the gunfire, vertical arms of azimuth lever 404 and of the elevation-lever 424 are connected respectively to the yoke and body of the second man's grip mechanism by means in every essential respect identical with what has just been described. The azimuth cables 430, 430 and elevation-cables 432, 432 appear in Fig. 23, leading off toward the right of the turret.

In each of the cables of the valve-controlling system is preferably included means for taking up slack, so that movement of the grip mechanisms may be communicated accurately to the valve-levers 404 and 424. As illustrated in detail in Fig. 24, into one extremity of a cylinder 434 is threaded a plug 436. The opposite extremity of the cylinder has an internal shoulder 438 against which the outer end of an expansion-spring 440 is seated. The cable 400, for example, is divided, one section passing through an axial bore in the plug 436 and being secured to a terminal 441 free to turn in a depression in the inner extremity of the plug, while the adjacent cable-end is fixed to a terminal 442 of less diameter than the internal diameter of the cylinder and bearing upon a washer 444 abutting against the spring. By adjustment of the plug longitudinally of the cylinder, the spring may be so loaded or put under such a normal degree of compression that its expansion will hold the cable taut, thus communicating the movement of the gunners' grip mechanisms accurately to the valves.

There may be included in the hydraulic mechanism within the casing 250 an unillustrated valve, to the stem 450 of which an arm 452 is attached (Figs. 2 and 22). A link 454 joins this arm to one arm of a bell-crank-lever 456 fulcrumed upon a bracket 458 depending from the top wall 44 of the turret. A second arm of the lever is connected by a link 460 to an arm 462 secured to the sleeve 224 (Fig. 11). These connections actuate the valve as the carrier *R* rotates, closing it to shut off pressure from the elevation-motor 334 when the carrier is turned beyond the desired limiting angle in either direction.

Having described the invention, what I claim as new and desire to secure by Letters Patent of the United States is:

1. The combination with a turret rotatable in azimuth, of a gun-carrier rotatable in elevation on the turret, a plurality of guns mounted on the carrier, a substantially round container beneath said carrier and concentric to the axis of rotation of the turret, said container enclosing annular troughs nested one within another, one trough being provided for each gun, motor means for elevating ammunition belts from the outer troughs to the outermost guns, said motor means being attached to the container, and ammunition-belt elevating motor means for the inner guns, said latter means being attached to the turret.

2. The combination with a turret rotatable in azimuth, of a gun-carrier rotatable in elevation on the turret, a plurality of guns mounted on the carrier, a container depending beneath said carrier and concentric to the axis of rotation of

the turret, said container having walls forming troughs one within another, one trough being provided for each gun, and motor means for elevating ammunition-belts from said troughs to said guns.

3. The combination with a turret rotatable in azimuth, of a gun-carrier rotatable in elevation on the turret, a plurality of guns mounted on the carrier, a portion depending from the turret having vertical walls defining ammunition-belt troughs one within another, one trough being provided for each gun, and means for elevating ammunition belts from said troughs to said guns.

4. The combination with a turret rotatable in azimuth, of a gun-carrier rotatable in elevation on the turret, a plurality of guns mounted on the carrier, a portion depending from the turret having vertical walls defining arcuate ammunition-belt troughs one within another, one trough being provided for each gun, means for elevating ammunition belts from one of said troughs to each of said guns, said elevating means including a yieldable wall along which the belt is elevated and which is displaceable by an undue accumulation of said belt, controlling means for said elevating means actuatable by movement of said yieldable wall, the said vertical walls being concentric with the axis of rotation of the turret and the innermost vertical wall enclosing a space constituting an entrance to the turret for the crew.

RENÉ E. DUPLESSIS.
